CLAIM

The ornamental design for a smartphone display with personalized audio invitations graphical user interface, as shown and described.

DESCRIPTION

FIG. 1 is a front view of a first embodiment of a smartphone display with personalized audio invitations graphical user interface in accordance with my new design; and,

FIG. 2 is a front view of a second embodiment of a smartphone display with personalized audio invitations graphical user interface in accordance with my new design. The broken lines illustrate an electronic device, which is the environment of the design, and form no part of the claimed design. The remaining broken lines illustrate portions of the display screen and portions of the graphical user interface that form no part of the claimed design.
